LOCKING DEVICE FOR ACCOUNTING MACHINES

Rudolph J. Moser, Dayton, Ohio, assignor to The National Cash Register Company, Dayton, Ohio, a corporation of Maryland

Application June 17, 1943, Serial No. 491,144

8 Claims. (Cl. 235—130)

1

This invention relates to accounting machines and similar business machines and is directed particularly to mechanism under control of an add-and-subtract totalizer or crossfooter, as they are known in the art, for preventing release of the machine during an operation following one in which an error has been made.

The invention is herein shown embodied in a machine of the general type shown in the following United States Letters Patent, and reference may be had to them for a complete showing and description of standard mechanism not fully disclosed herein:

Patents No. 1,693,279, issued November 27, 1928, to Walter J. Kreider; Nos. 1,619,796 and 1,916,535, issued March 1, 1927, and July 4, 1933, respectively, to Bernis M. Shipley; No. 2,141,332, issued December 27, 1938, to Charles H. Arnold; No. 2,175,346, issued October 10, 1939, to Maximilian M. Goldberg; and No. 2,262,258, issued November 11, 1941, to Bernis M. Shipley, Pascal Spurlino, and Everett H. Placke; and also the co-pending application for Letters Patent, Serial No. 381,962, filed March 6, 1941, by Pascal Spurlino, Mayo A. Goodbar, and Marvin D. Frost, for accounting machines, which issued into Patent No. 2,345,839 on April 4, 1944.

The machine illustrated herein as embodying the present invention is well adapted for use by public utility companies and especially in the bookkeeping departments thereof, where the various items involved in each customer's account for certain specified periods of time are listed, classified, and totaled, and where also bills are made out which are sent to the customer, showing the amount of service which has been rendered to him and the cost thereof.

The system chosen to illustrate the present invention is one used by public utility companies or municipalities for keeping records of the water used by industries or the peoples of the municipalities.

It is, however, not intended to limit this invention in any way to the recording of water service from meters, as it is very readily susceptible of use in connection with public utility companies and other municipalities who have control of, for example, the gas and electrical supplies, equipment, and service for the peoples of those municipalities.

The machine used to illustrate the invention is provided with an add-and-subtract totalizer, usually referred to as a "crossfooter," which is of the type known in the art as a "split" totalizer. In the present instance, this totalizer is split into

2

three sections, one for "meter readings," one for "gross amount," and one for "net amount."

The data entered into the machine is taken from a meter reader's book, which book is supplied to the operator of the machine illustrated herein with all the items that are to be posted on the bill already entered therein, so that all that the operator need do is read the items from the book, set them up on the keyboard, and enter them into the machine by depressing appropriate control keys.

In the system illustrated herein, the operator first sets up the amount of the "present reading" on the left-hand section of the keyboard and releases the machine for operation by depressing the "present reading" key, and during such operation the amount of the "present reading" of the meter is entered into the subtract side of the left-hand section of the crossfooter.

Next, the operator scans the meter reader's book to determine the amount of the "previous reading" of the meter, then sets that amount up on the left-hand section of the keyboard, and releases the machine for operation by depressing the "Previous reading" key, and during such operation the amount of the "previous reading" is entered into the plus side of the left-hand section of the crossfooter.

Next, the operator scans the meter reader's book to determine the amount of "consumption" noted therein, then sets that amount up on the left-hand section of the keyboard. Then the operator scans the meter reader's book to determine the "gross" amount of the bill and sets that amount up in the middle section of the keyboard, and finally scans the meter reader's book to determine the "net" amount of the bill and sets that amount up on the right-hand section of the keyboard. After these three items have been set up on the keyboard, the operator depresses an appropriate key, then releases the machine by depressing a motor release key, and, during the ensuing operation, the amount of water consumed is added into the plus side of the left-hand section of the crossfooter; the "gross" amount to be charged is entered into the plus side of the center section of the crossfooter; and the "net" amount to be charged is entered into the right-hand section of the crossfooter.

If, during the three entries described above, the amounts of the "present reading," "previous reading," and "consumption" were properly set up on the keyboard, the plus wheels of the left-hand section of the crossfooter will be standing at zero. However, if an error occurred in the entry of any

one or more of these three amounts, this section of the crossfooter will have an amount standing thereon, but at this time the operator is not aware of the fact that an error has been made.

It is an object of the invention to provide a means to notify the operator that an error has been made in entering the above three items, and the invention contemplates notifying the operator by locking the machine against release to start a new series of entries. Therefore, when the plus wheels of the left-hand section of the crossfooter are not standing at zero after the amount of consumption has been entered, the depression of the "Present reading" key will not release the machine for operation.

The above-described series of entries applies to the entry of data relating to one meter. Some users of water, known as "commercial users," have two meters, one for commercial use of water and one for industrial use. The meter reader's book for such a customer has entered therein two series of amounts like that described above for one meter. In entering the two series of amounts, the operator reads them from the meter reader's book in the same sequence as described above. That is, he will enter the amount of present reading, previous reading, and the water consumption, gross amount to be charged and net amount to be charged for one meter, and, if no error is made in the entry thereof, the operator immediately begins entering the amounts of present reading, previous reading, and the water consumption, gross amount to be charged and net amount to be charged for the second meter readings. In printing a bill for a commercial user, the entry of the second water consumption and gross and net amounts to be charged is immediately followed by a total-taking operation to print the total gross and net amounts to be charged for the two meter readings.

During the entry of the second series of entries—that is, the entries for the second meter—an error may have been made, so that, at the end of the operation in which the second consumption gross and net amounts are printed, the plus wheels of the left-hand section of the crossfooter will not be at zero. Under this condition, it is desirable to prevent release of the machine by depression of the "Present reading" key for the next succeeding customer, but it is desired to release the machine for printing the totals of the two meter readings, so that the customer's bill can be completed by a total-taking operation.

It is an object of the invention to provide a means to prevent release of the machine by depression of the "Present reading" key when the error has been made in entering said data, but to permit a total-taking operation even though the left-hand section of the crossfooter is not at zero, and to provide a control maintaining the non-releasing condition of the machine by the "Present reading" key even after said total-taking operation, so that the operator will be notified that an error was made in the said entries when attempting to enter the present reading for the next succeeding customer account. This will give the operator an opportunity to correct the error on the bill before proceeding to enter the next customer's data.

Another object of this invention is the provision of means to lock the machine against release under control of the totalizer when the latter is not at zero at the end of an operation, and means to retain such locking means in its effec-

tive position after said totalizer has been reset to zero during a total taking operation.

Another object is the provision of a novel means to set up a condition during one operation to prevent release of the machine during a subsequent operation when an error has been made during an operation previous to said one operation.

With these and incidental objects in view, the invention includes certain novel features of construction and combinations of parts, the essential elements of which are set forth in appended claims and a preferred form or embodiment of which is hereinafter described with reference to the drawings which accompany and form a part of this specification.

In said drawings:

Fig. 1 is a diagrammatic view of the keyboard of the machine according to one system in which the invention can be used.

Fig. 2 is a fragmentary view taken alongside one of the control banks of keys and shows a portion of the locking mechanism of the present invention, and also shows a portion of the total plate set under control of the keys of row 1.

Fig. 3 is a detail view showing a portion of a crossfooter in the disengaged position and illustrates also a portion of the locking mechanism controlled thereby.

Fig. 4 is a detail view of a portion of the locking mechanism shown in Fig. 2, and shown in the normal position.

Fig. 5 is a detail view of the locking mechanism shown in the locking position and also shows the novel means to retain it in such position, and shows the positions which the parts assume just before the crossfooter is moved into engaging position during a total operation.

Fig. 6 is a plan view, partially broken away, showing the regular release mechanism for the machine, a portion of the crossfooter for registering the meter readings and consumption, and the locking mechanism controlled by the crossfooter for controlling the release of the machine. Also there are shown in diagrammatic form the key stems of the control keys and their relationship to the control bars which they operate for operating and controlling the locking mechanism associated with the releasing mechanism.

Fig. 7 is a detail view of a portion of the locking mechanism operated under control of the control bar associated with row 1, or the row of total keys.

GENERAL DESCRIPTION

Described in general terms, the machine embodying the present invention is of the same general type as that disclosed in the Shipley and Arnold patents referred to above, and also the Spurlino et al. patent referred to. Like the machines disclosed in such patents, the present machine is provided with a plurality of totalizers and column printing mechanism. The totalizers are operated by differential mechanism under the control of amount keys, while the selection of the totalizers to be operated is accomplished through differential mechanism under control of the control keys provided for that purpose.

The above-mentioned differential mechanism also serves to adjust the printing mechanism to print the various amounts and data relating thereto on record material.

The present invention, however, is concerned chiefly with means for locking the machine against release when an error in the setting up

of certain data, and the registering thereof, has been made during the registration of a previous operation.

For this purpose, the machine keyboard is divided into sections, otherwise known as a split keyboard, having the left-hand group of keys for the purpose of setting up the meter readings and the consumption, the center group of amount keys for the purpose of setting up the gross amount of the bill, and the right-hand group of amount keys for setting up the net amount and forfeited discounts, sewer charges, etc.

The four rows of control keys are used for selecting the various totalizers and also for clearing the totalizers and controlling the printing, as has been described in connection with the above-mentioned patents.

When an operator is registering what is known as a multiple-meter registration, it is a case where the customer uses two meters; one, for example, for commercial use and the other for industrial use, or it might be where a person in an apartment house or large residence uses one meter for drinking water and general household use and a second meter for laundry use.

In either event, the meter reader is required to read both meters, and, when the bill is sent to the customer, both meter readings of present, previous, and consumption, and the gross and net amounts of those meters, are set up on the machine and totaled by the totalizers, and finally the amount of the total bill is obtained by the depression of the Total bill key. It is with this particular type of case that the present invention is involved. In other words, should an error be made during the setting up of the present, previous, or consumption of the second meter, the operator would take the total of both readings by the operation of the Total bill key. However, when the operator attempted to set up the present reading from a meter of the next customer, the machine could not be released upon the depression of the Present reading key, which is normally a key that releases the machine for operation, because, during the operation preceding the total operation, the machine releasing means which is under control of the "Present reading" key was locked, and, during the total operation immediately following, a retaining means for said locking means was rendered effective to retain such locking condition to prevent an operation subsequent to said total operation.

DETAILED DESCRIPTION

Keyboard

The keyboard of the machine used to illustrate a system with which the present invention is involved has 15 rows of amount and data keys divided into three sections. The first five left-hand rows of keys 20 are used for setting up the present meter reading, the previous meter reading, and the amount of consumption of water. The net five rows of keys 21 are used to set up the gross amount to be charged for the water consumed, and the next five rows of keys 22 are used to set up the net amount to be charged for water used, forfeited discounts, sewer charges, arrears, etc., in connection with a water system which may be operated by a public utility company or by a municipality.

There are four rows of control keys marked "Row 1," "Row 2," "Row 3," and "Row 4." The keys 23 of row 1 are what are known in the

art as "Total" keys. The "Clear row 3" and "Clear row 4" keys 23 are used to clear the totalizers in the machine associated with the keys of rows 3 and 4. The "Correction" key 23 is used to clear the crossfooter and the totalizers when an error has been made that is discovered immediately. The "Arrears balance" key 23 is used to clear the machine after partial payments and balance forwards have been registered, so as to get the new balance of whatever the customer is in arrears.

The "Total bill" key 23 is used to clear the machine and take the total of a multiple-meter bill. The "Total bill" key, the "Arrears balance" key, and the "Correction" key 23 are what are known in the art as machine release keys; that is, the depression of any one of these keys alone will release the machine for operation. The "Clear row 3" and "Clear row 4" keys are non-release keys and must be used in connection with keys in rows 3 and 4 to clear the totalizers for those rows.

The keys 24 of row 2 are used to register various transactions in the machine. The "Credit balance" key 24 is a non-release key and is used to clear the overdraft when used in connection with the "Arrears balance" key 23 of the total row. The "Part payment" key 24 is a machine release key and releases the machine upon depression. The "Present reading" key 24 is a machine release key and is used when the operator sets up the present reading of the meter with the amount keys 20. The "Full payment" key 24 is used when a customer completes a balance due. It is a machine release key. The "Previous reading" key 24 is a machine release key and is used when the previous meter reading is registered. The "Balance forward" key 24 is a machine release key and is used in a posting operation. The "Multiple line" key 24 is a non-release key and is used in conjunction with all keys 26 of row 4, and the "5th step" key 24 of row 2 when a multiple-meter bill is registered. The "5th step" key 24 is one of the graduated rate scale keys used in the setting up of amounts gross and net. The "Lock proof" key 24 is used to release, or "take off," the lock for the machine release and is not a machine release key but is operated in conjunction with the "Arrears," "Sewer charge," or "Forfeited discount" keys 25 when an error has been made in the setting up of the meter readings or consumption.

The "Reinsert ledger" key 25 is a machine release key and is used when a ledger card is reinserted after an error. The "Grand total" key 25 is a release key and is used with "Clear row 3" key 23. The "Arrears" key 25 is a release key and is used to release the machine when amounts paid towards arrears balance are registered. The "Sewer charge" key 25 is used in connection with setting up charges for this purpose. The "Forfeited discount" key 25 is used likewise for setting up the amount of forfeited discount. These last two keys are machine release keys. The "Commercial" and "Industrial" keys 25 are non-release keys and, of course, are used for segregating whether the water is used for industrial use or for commercial use. The "Residential" key 25 likewise is used whenever the water used is for residential purposes.

The keys 26 of row 4 are all machine release keys and are used for segregating the amounts depending upon the size of the meters used, such as $\frac{5}{8}$, $\frac{3}{4}$, 1", $1\frac{1}{2}$ ", or 2", and the 1st, 2nd, 3rd,

and 4th step keys 26 are used in connection with a graduated scale of charges for water.

The differential mechanism associated with the amount keys, and also all of the control keys of rows 1, 2, 3, and 4, is not shown here, as it is identical with those shown and described in the above-mentioned patents.

The keys are mounted in the usual type of key frames 30 (shown in Fig. 2), which are supported by rods 31 and 32 carried by the side frames 33 and 34 (Fig. 6) of the machine.

Each of the keys of each of the control rows 1, 2, 3, and 4 cooperates with a control bar for its respective row. In Fig. 2 is shown a control bar 35 mounted on a pair of arms 36 supported by the frame 30. This control bar 35 is associated with the keys 24 of row 2. A spring 37 tends to move the bar upwardly to keep projections 38 on said bar in contact with key pins 39 of all of the keys in row 2 except the "Present reading" key and the "Multiple line" key, as is clearly shown in Fig. 6. The pins 39 of the Present reading and Multiple line keys are shown diagrammatically shorter than the rest of the keys in Fig. 6. However, the control bar 35 has no projection 38 associated with the pins 39 of the Present reading key 24 or the Multiple line key 24, and therefore depression of either of these keys will not move the bar 35. However, depression of any of the other keys in this row will move said bar 35 downwardly and toward the left, as viewed in Fig. 2, for a purpose to be described later.

Associated with the keys 26 of row 4 is a control bar 40 having projections 41, which cooperate with pins 42 of the keys 26. This control bar 40 has a projection 41, which cooperates with each and every one of the keys 26 of row 4, so that depression of any one of these keys will move this bar 40 toward the left, as viewed in Fig. 5. This bar 40 is mounted on a pair of arms 43 (only one of which is shown), which are supported by a key frame like the key frame 30.

Associated with the keys 25 of row 3 is a control bar 44 (Fig. 6), which has a projection 45 opposite the Reinserted ledger key 25 only, to cooperate with its pin 46. This key is the only key 25 in row 3 which will operate the bar 44. This bar 44 is rigidly connected by means of a coupling pin 47 to the bar 40. The purpose of coupling this bar 44 to the bar 40 will be described later.

Associated with the Total keys 23 of row 1 is a bar 50 (Figs. 6 and 7) having notches 51 to cooperate with pins 52 of the Total bill key, the Arrears balance key, and the Correction key, so that the depression of any one of these keys will move this bar 50 downwardly, as viewed in Fig. 7, for a purpose to be described later.

Totalizers

As has been stated previously, the machines in which the present invention is adapted to be used are usually provided with three lines of totalizers, as shown in the above-mentioned patents. One of these lines is a line having a plurality of add-and-subtract totalizers or crossfooters arranged side by side in a formation known in the art as a "split totalizer." In the present set-up, there are a crossfooter for the meter reading, a crossfooter for the gross amount, and a crossfooter for the net amount.

However, the present invention involves only the crossfooter which is associated with the meter readings and the consumption, and therefore

only so much of the crossfooter will be shown as is necessary to show how this controls the release of the machine when the operator has made an error in setting up either the present reading, the previous reading, or the consumption.

The crossfooter associated with the meter readings and the consumption is shown particularly in Figs. 3 and 6, mounted in the usual frame 60, which is slid back and forth on a rod 61 carried by the side frames 63 and 64. The lower end of the totalizer frame 60 carries the usual shouldered roller 62, which is operated by a drum cam (not shown) to shift the crossfooter laterally for the purpose of selecting either the plus side or the minus side thereof. As the crossfooter is shifted laterally, it is guided by the usual bracket 63, shown in Fig. 3.

The crossfooter associated with the meter readings and the consumption consists of five digits, three of which are shown in Fig. 6. Each denominational digit of the crossfooter comprises a minus wheel 65 and a plus wheel 66, which are geared together to move in opposite directions, as is clearly shown in the above-mentioned patents to Shipley, and also in United States Patent No. 2,375,594, issued on May 8, 1945, to Pascal Spuriano, William M. Carroll, Arthur Ray Colley, and Alfred G. Kibler. Secured to the plus wheel 66 is a second plus wheel 67, and secured to this plus wheel 67 is a disk 68 having a notch 69. The second plus wheel 67 is used for a purpose not pertinent to the invention described herein.

When the crossfooter is at zero, the minus wheels 65 stand at 9, and the plus wheels 66 and 67 stand at zero, and, when the crossfooter is in this condition, a pawl 70 engages the notch 69. This pawl 70 is secured to a shaft 71, which is carried by the totalizer frame 60. As shown in Fig. 6, there is a pawl 70 for each denominational order of the crossfooter.

When the totalizer is in its disengaged position, as shown in Figs. 2, 3 and 5, the pawl 70 is held either in engagement with the notch 69, as shown in Figs. 2 and 3, or in contact with the periphery of the disk 68 by a torsion spring 72 having one end secured in the totalizer frame 60 and the other end to a pin 73 of an arm 74, which is secured to the shaft 71. Also secured to the shaft 71 is an arm 75, which is adapted to cooperate with a pin 76 secured in the side frame 33.

Since the shaft 71 is carried by the totalizer frame 60, it will receive a movement downwardly when the totalizer is engaged with the actuators 77 shown in Fig. 6. During this downward movement of the crossfooter and the shaft 71, the arm 75 strikes the pin 76 and rocks the pawls 70 counter-clockwise to disengage them from the notches 69 just prior to the time the crossfooter becomes fully engaged with the actuators 77, so that the totalizer can be properly operated by the actuators.

Then, after the totalizer has been operated to either add or subtract, as the case may be, it is disengaged from the actuators 77, and during this disengagement, as the arm 75 leaves the pin 76, the spring 72 will rock the shaft 71 and the pawls 70 clockwise until the pawls 70 engage the notches 69 of the disks 68, assuming, of course, that the adding wheels 66 and 67 of the totalizer stand at zero. If any one of the wheels does not stand at zero, then the pawl coacting with such wheel engages the periphery of the disk 68 and consequently will not be rocked quite so far in a clockwise direction by the spring 72 as it would be if it could engage the notch 69. Since all the

pawls 70 are secured to shaft 71, all the pawls are held in such position by any one disk. The purpose and function of this will be described later.

Machine releasing mechanism

The complete machine releasing mechanism has not been shown, as it is not thought necessary to do so. It is thought that it is sufficient to show only one main shaft of the releasing mechanism, which shaft 80 is mounted in the side frames 33 and 34. This shaft and the mechanism for operating it are fully illustrated and described in the above-mentioned Shipley patents. To release the machine, this shaft 80 is given a clockwise movement, as viewed in Figs. 2, 3, 4, and 7. Secured to this shaft is an arm 81, which is rocked clockwise along with the shaft 80 when the machine is released for operation.

There are certain keys in the machine, as above stated, which are known as release keys and which, when depressed, will set up a condition whereby the shaft 80 will be rotated in a clockwise direction to release the machine.

In row 1, the "Total bill" key, the "Arrears balance" key, and the "Correction" key 23 are machine release keys. In row 2, the "Part payment," "Present reading," "Full payment," "Previous reading," "Balance forward," and "5th step" keys 24 are machine release keys; in row 3, the "Reinsert ledger," "Grand total," "Arrears," "Sewer charge," and "Forfeited discount" keys 25 are machine release keys; and in row 4, all of the keys 26 are machine release keys. Therefore, the depression of any one of the keys just mentioned will set up a condition whereby the shaft 80 and the arm 81 will be rocked clockwise to release the machine.

The arm 81 has a flange 82 bent at right angles thereto to cooperate with mechanism to be described later, to prevent the necessary clockwise movement of the shaft 80 on certain types of operations and when certain keys are depressed should the crossfooter associated with the meter readings and consumption not be at zero, which occurs, as stated above, when the operator has made a mistake in the setting up of the present reading, the previous reading, or the consumption.

Differential mechanism

The differential actuators 77 (Fig. 6), associated with the rows of keys 20 for setting up the meter readings and the consumption, are the only part of the differential mechanism shown in this application. However, the differential mechanism used is the same as that shown in the previously-mentioned Shipley patents, and for a complete understanding thereof reference may be had to these patents. This applies also to the differential mechanisms associated with the "Gross amount" keys 21 and the "Net amount" and "Forfeited discount" keys 22.

None of the differential mechanisms associated with the control rows of keys 24, 25, and 26 have been shown in this application, as it is not felt necessary that they be shown herein in order to have a complete understanding of the invention, and therefore reference may be had to the above-mentioned Shipley patents for this mechanism, if it is desired.

Neither has the differential mechanism associated with the total row of keys 23 been shown, and for a disclosure and description of such mechanism reference may be had to the previously-mentioned Shipley, Spurlino, and Placke Patent No. 2,262,258.

Locking mechanism for the machine releasing mechanism

As has been previously stated, the machine release shaft 80 is prevented from moving its full clockwise movement to release the machine for certain kinds of operations—for example, a "Present reading" operation whenever an error has been made in the setting up of the meter reading of the present, previous, or the consumption of the previous series of operations, so that the crossfooter will not come to zero at the end of such a series.

However, this error may not be discovered during the registration of that particular transaction, but it will be discovered upon the subsequent operation, when the operator attempts to release the machine by depressing the "Present reading" key 24, after having set up on the meter reading keys 20 the present reading of the next customer's meter, or it might be the same customer's second meter, where a customer has two meters, one for commercial use and one for industrial use.

The error might also be discovered if the customer had other charges to be put on his bill, such as "Forfeited discount," "Arrears," or a "Sewer" charge. These keys 25 also could not release the machine because they do not cooperate with the control bar 44, which is tied to the lock release control bar 40.

The mechanism for causing this lock-up of the machine—that is, the prevention of the release of the machine when the "Present reading" key 24 is depressed—will now be described.

First let it be assumed that the crossfooter shown in Figs. 2, 3, and 6 is standing in its cleared position, while the wheels 65 on the minus side stand at 99999 and both of the plus wheels 66 and 67 of the crossfooters stand at 00000. Assuming that the present reading of the meter was 765, this amount is set up on the keys 20 and 765 is added to the minus wheels 65 of the crossfooter, so that these wheels now read 00764, and at the same time, this 765 is subtracted from the plus wheels 66 and 67, so that these wheels now stand at 99235. On the next operation, the operator sets up the previous reading, which, for example we will say is 532. This amount is added to the 99235 of the plus wheels 66 and 67, so that they now stand 99767. This same amount 532, which is the previous meter reading, is subtracted from the minus wheels 65, so that these wheels now stand 00232. This would leave the consumption at 233, and therefore the operator now sets up the amount 233 on the keys 20, which amount is added to the plus wheels 67 and 66, so that they now stand at 00000, and this amount 233 is subtracted from the minus wheels 65, so that they now read 99999. At the end of this operation, the notches 69 in the disks 63 are in the positions shown in Figs. 2 and 3, and the pawls 70 will engage those notches and the operator may then continue to set up the transactions of present and previous meter readings and the consumption for the next customer.

However, if, instead of setting up the consumption 233, the operator had erroneously set up the consumption as 333, then this amount of 333 would have been added to the plus wheels 66 and 67, leaving these wheels standing at 00100 instead of 00000. At the same time, this amount 333 would have been subtracted from the minus wheels 65, which stood at 00232. Therefore these wheels would now stand at 99899, and therefore the notch 69 would not be opposite the pawl

70 of the hundreds order digit, but would be in the position shown in Fig. 5 at the end of this operation, and, by means to be described hereinafter, it will be impossible for the operator to go on for the next operation, which normally is the setting up of the present reading for another meter, because, upon the depression of the "Present reading" key 24, the release shaft 80 would be blocked against its proper clockwise movement. This mechanism will now be described in detail.

Secured to shaft 86 supported by the side frame 34 and a plate 87 is a yoke 89. This yoke 89 has a long arm 98, and a spring 91 connected thereto holds a finger 92 of the arm against a stationary stud 93 carried by the plate 87. This is the normal position of the yoke 89, as shown in Figs. 2 and 4.

Rigidly secured to the previously described shaft 71 is an arm 94 normally held in the position shown in Fig. 2 by the previously described spring 72.

It will be recalled that the shaft 71 is moved downwardly when the crossfooter is moved into engagement with the actuators 77, and also that this shaft 71 receives a counter-clockwise movement just before the crossfooter is engaged with the actuators, occasioned by the contact of the arm 75 with the stationary stud 76 in the frame 33. This counter-clockwise movement of the shaft 71 positions the arm 94 beneath the yoke 89, after the shaft 71 has been moved downwardly with the totalizer frame 69.

Assuming now that the operator made a mistake, as mentioned above, and entered as the consumption the number 333 instead of 233, this would leave the notch 69 in the hundreds order disk 68 in the position shown in Fig. 5 when the crossfooter is disengaged from the actuators 77. Consequently, the pawls 70 could not be rocked clockwise by the spring 72, as described earlier, upon the disengagement of the crossfooter from the actuators 77, and therefore, as the totalizer is disengaged or moved into the position shown in Fig. 5, the upward movement of the shaft 71 causes the arm 94 to strike the yoke 89 and rock said yoke 89, the shaft 86 and the arm 99 in a counter-clockwise direction from the position shown in Fig. 2 to the position shown in Fig. 5. Pivoted on a rod 95 supported by the machine side frames 33 and 34 is an arm 96, which is normally held in contact with a stud 97 on the arm 99 by a spring 98 connected to pins on the arms 99 and 96. Secured to the arm 96 is a yoke 99 connecting an arm 100 also pivoted on the rod 95. The end 101 of the arm 100 is normally in the position shown in Fig. 4, which is above the flange 82 of the release arm 81 and the release shaft 80.

From the above description it will be clear that, when the arm 99 is rocked counter-clockwise by the arm 94, as described above, the spring 98 will rock the arm 96, the yoke 99, and the arm 100 in a clockwise direction from the position shown in Figs. 2, 4, and 7 into the position shown in Fig. 5, whereupon the end 101 of the arm 100 is directly in the path of movement of the flange 82 on the release arm 81 of the release shaft 80 and consequently will prevent sufficient clockwise movement of the arm 99 to release the machine. Assuming that an "arrears" charge, a "sewer" charge, or a "forfeited discount" charge had to be added to this bill, the operator depressed the appropriate key 25, but, due to the above error having been made, the machine can-

not be released by depression of any of said keys.

Since the machine will not release upon the depression of any of the keys just mentioned, the operator knows that he has made a mistake, and he may now release the locking arm 100; that is, move it out of the path of the flange 82 of the release arm 81 by depressing the Lock proof release key 24 in row 2 and then depressing the appropriate key 25 to enter an "arrears," "sewer," or "forfeited discount" charge.

The "Lock proof" key 24 cooperates with the previously described control bar 35 (Figs. 4 and 6), which carries a pin 110, which cooperates with a finger 111 of an arm 112 pivoted on the rod 95.

- 15 This bar 35 is associated with the Lock proof key 24, and consequently depression of this key rocks the arm 112 in a counter-clockwise direction, whereupon a slot 113 thereof, by its engagement with a pin 114 of an arm 115 secured to a shaft 116, rocks said shaft in a clockwise direction. This shaft is carried by the plate 87 and another plate 117 (Fig. 6). Also secured to the shaft 116 is an arm 118 having a pin 119, against which a projection 120 of the arm 95 came into contact 20 when the arm 96 was rocked in a clockwise direction by its spring 98 in the manner previously described.

Therefore, the clockwise movement of the shaft 116 will rock the arm 118 clockwise and the pin 119 will rock the arm 96, the yoke 99, and the arm 100 counter-clockwise to move the end 101 of the arm 100 from the path of movement of the flange 82 of the release arm 81, after which the machine may be released for operation by depression of an appropriate release key 25. In order to show the proper data on the bill, the operator corrects the bill by hand-written figures after the series of operations has been completed.

During the operation of the machine with the "Lock proof" key 24 and the appropriate key 25 depressed, when the crossfooter is disengaged, the arm 100 is again brought in front of the flange 82 of the release arm 81, and the machine is therefore again locked due to the error still in 45 the meter reading crossfooter.

The operator now corrects the meter crossfooter by clearing the same by releasing the machine by depressing the correction key 23 in row 1. This key takes off the lock for the release shaft in the following manner.

The control bar 50 (Figs. 6 and 7) of row 1 has a slot 51 cooperating with the "Correction" key 23, so that depression of this key moves the bar 50 to the left (Fig. 6), and a pin 125 thereon rocks an arm 126 counter-clockwise. This arm 126 has a finger 127 normally contacting a pin 128 on the arm 112. Therefore, this arm 112 is rocked counter-clockwise by the bar 50, whereupon the arms 115 and 118 are rocked clockwise 60 and the pin 119 rocks the arm 96, the yoke 99, and the locking arm 100 from the position shown in Fig. 5 into the position shown in Figs. 2, 4, and 7.

During this clearing operation of correction, 65 the notches 69 will all again align themselves with the ends of the pawls 70, and consequently, when the crossfooter is disengaged, the arm 94 will not be in the path of the yoke 99, since the ends of the pawls will be engaged with the notches 70 69 under the influence of the spring 72, and consequently the stud 97 will hold the arm 96, the yoke 99, and the arm 100 in the position shown in Figs. 2, 4, and 7.

Assuming now that the operator is going to 75 make up what is known as a multiple line bill,

where one customer has two meters for the registration of water used—one, for example, for commercial use and the other for industrial use—and that the meter readings of the commercial use are set up first, the first being the present reading, the previous reading, and the consumption, all of which the operator sets up correctly, then he sets up the meter reading from the industrial meter, and, during the registration of the meter reading from this industrial meter, an error is made, so that the crossfooter will not come at zero, and consequently the notches 69 in one or more of the disks 68 will not be opposite the ends of the pawls 70. However, the operator at this time does not discover the error because, after having set up the consumption, the next operation for the operator to do in order to obtain the total amount due from both meters is to release the machine by operating the "Total bill" key 23, whereupon the crossfooter will be 20 returned to its zero position.

During the disengagement of the crossfooter, after the entry of the consumption, wherein the crossfooter was not cleared, due to the error, the arm 90 was rocked from the position shown in Figs. 2, 4, and 7 into the position shown in Fig. 5, as has already been stated, whereupon the spring 98 moves the end 101 of the locking arm 100 into the path of the flange 82 of the releasing arm 81.

At the same time, an arm 131, secured to the shaft 83, is moved from the position shown in Fig. 2 into the position shown in Fig. 5. This movement of the arm 131 occurs during the entry of the first item of the transaction wherein the error was made when registering the meter readings or the consumption from the industrial meter in connection with the multiple line bill above mentioned.

Associated with the "Total bill" key 23 is a differentially positioned total plate 132 (Figs. 2 and 6), which plate is adapted to be set into different positions under control of the keys 23 of row 1 for the total row, as it is sometimes called, by mechanism which is fully illustrated and described in the previously mentioned Shipley, Spurlino, and Placke Patent No. 2,232,258.

When the "Total bill" key 23 is depressed, the total plate 132 (Fig. 2) is rocked clockwise until the bottom of a depression 133 of a slot 134 in the plate 132 cooperates with a roller 135 on an arm 136 pivoted on the shaft 116, thus causing a counter-clockwise movement of the arm 136. Integral with this arm 136 is a finger 137, which, upon the counter-clockwise movement of the arm 136, is positioned directly in front of a square stud 138 carried by the arm 131, since the arm 131 has been previously moved from the position shown in Fig. 2 to that shown in Fig. 5, during the entry of the transaction of the setting up of the meter readings for the consumption from the industrial meter, as mentioned above. The timing of the movement of the total plate 132 is such that it is fully set before the cross footer is lowered into engaging position.

Since the total plate 132 is differentially positioned before the crossfooter is in engaging position, and since the plate 132 remains in the position into which it was set at the completion of an operation, and until it is differentially moved during a subsequent operation, either to its normal position shown or to another position under control of one of the other keys 23 of the total row, the arm 136 and the finger 137 will be retained in the position shown in Fig. 5

at the completion of the total bill operation and consequently hold the arm 131 in the position shown in Fig. 5. This permits the locking arm 100 to be positioned in front of the releasing flange 82 of the release arm 81, and prevents release of the machine when the operator attempts a subsequent operation of the machine by the depression of the "Present reading" key 24 to register the meter readings of a subsequent customer.

Since the finger 137 is moved into the path of the arm 131, before the crossfooter is lowered into its engaging position, said arm 131 is not released to the action of the spring 91 when the crossfooter is lowered. When the crossfooter is cleared during the operation in which the "Total bill" key 23 is depressed, all the notches in the disks 68 are alined with the pawls 70, thus permitting the pawls 70, the shaft 71, and the arm 94 to rock clockwise under action of spring 72, and thereby withdraw the arm 94 from the path of the flange 89. Thereafter, when the crossfooter is disengaged, the arm 94 moves idly. However, at this time, the arm 131 is in position in front of stud 138 on arm 131 and holds arm 90 in the position wherein the locking arm 100 is in front of the release arm 81. Thus, even though the crossfooter is standing at zero, the machine can not be released for a subsequent operation with the "Present reading" key depressed, thus indicating that an error was made in the statement just completed.

Now on the subsequent operation, as above mentioned, since the operator discovers that an error had been made when he pressed the "Present reading" key 24 when attempting to register the meter readings of a subsequent customer, it then becomes necessary for him to release the lock arm 100 from the path of movement of the flange 82, and in order to do so he depresses the "Lock proof" key 24 in conjunction with the "Present reading" key 24. The depression of this "Lock proof" key 24 through the control bar, as described above, rocks the arm 118 (Fig. 7) clockwise, whereupon the pin 119 raises the arm 96, the yoke 99, and the locking arm 100, thus moving the arm 100 out of the path of movement of the flange 82 of the release arm 81, and then the operator may proceed to set up the meter reading by means of the keys 20 (Fig. 1) and enter this present meter reading into the machine by depressing the "Present reading" key 24.

Since the entry of this present meter reading does not involve the depression of any of the keys of row 1, the total plate 132 will be automatically differentially positioned back into the position shown in Fig. 2, whereupon the slot 134 will rock the arm 136 and the finger 137 clockwise to remove the finger 137 from in front of the stud 138 of the arm 131. After the removal of this finger 137 from the stud 138, the spring 98, having been put under tension by the counter-clockwise movement of the arm 96, will rock the arm 96 and the arm 131 from the position shown in Fig. 5 to that shown in Fig. 2, wherein the pin 37 of the arm 96 again contacts the under side of the arm 99. This movement of the arms 96 and 131 is also aided by the spring 91 in conjunction with the spring 98.

If no error was made during the entry of the various items of a multiple-line bill, then, at the conclusion of the last entry, the disks 68 are in the position shown in Fig. 2, and the arm 94 is in the ineffective position and does not hold the arm 131 in the locking position. Thus the rela-

tionship between the finger 127 and the arm 131 is as shown in Fig. 2. With the parts in such position and a "Total bill" operation initiated, the total plate 22 rocks the finger 127 counter-clockwise, as in the operation previously described. However, since the stud 135 is out of range of the finger 127, the rocking of finger 127 does not come in front of said stud and therefore has no control over the locking arm 100.

Special Lock proof release keys

Since, during the entry of the present meter reading of any meter, the crossfooter wheels 66 and 67 (Fig. 6) are moved out of their normal positions, the locking arm 100 is moved into locking position in front of the flange 82, at the end of the very first transaction. Therefore, during the entry of the previous reading, it is necessary that this lock arm 100 be removed from the path of the flange 82, and this is accomplished by the depression of the "Previous reading" key, the pin 29 of which cooperates with its associated projection 33 on the control bar 35 to rock the arm 112, as has been previously described. This rocking of the arm 112, as will be remembered, rocks the arms 115 and 116 clockwise, whereupon the stud 110 rocks the arm 99, the yoke 88, and the arm 100 counter-clockwise to remove the locking arm 100 away from the flange 82 of the release arm 81.

At the end of this transaction—that is, the entry of the previous reading—the lock arm 100 will again be positioned in front of the flange 82, and consequently, when the operator sets up the consumption, this arm must be removed.

When the amount of the bill is set up, one of the keys 26 in row 4, or the "5th step" key 24 in row 2, is depressed to select the proper totalizer into which the amount of the bill is to be added, because it will be remembered that, when the consumption is set up on the keys 20, the gross amount of the bill is set up on the keys 21 and the net amount of the bill is set up on the keys 22, and therefore, in order to have these gross and net amounts go into the proper totalizers, they must be selected by one of the keys 26 or the fifth step key 24. Therefore, the depression of the "5th step" key 24 will move the bar 35 the same as the "Previous reading" key to remove the lock arm 100 from in front of the flange 82.

Associated with each of the keys 26, as has been previously mentioned, is a control bar 40, shown in Figs. 5 and 6, which has projections 41 associated with the pins 42 of each of the keys 26 of this row. Consequently, when any key in this row is depressed, the control bar 40 will be moved to the left, as viewed in Fig. 5, whereupon a pin 140 carried by this bar 40, through its contact with an arm 141 integral with the lock arm 100, will rock said arm 141 and consequently the lock arm 100 in a counter-clockwise direction and move it out of the path of movement of the flange 82 of the release arm 81.

However, at the end of the entry of this consumption, if an error has been made, as has been described previously, the lock arm 100 will again be moved downwardly into the path of the flange 82 of the release arm 81 to lock the machine and prevent the entry of a subsequent present reading of a meter until the operator has made a correction of the error which was made during the previous transaction.

Since all the functions of the various locking and interlocking features have been fully explained during the detailed explanation of these

mechanisms, it is not thought necessary to give any general descriptive operations of the machine.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

What is claimed is:

1. In a machine of the class described adapted to make a plurality of operations to complete a single transaction, said operations comprising adding, subtracting, and total-taking operations, the combination of a machine release shaft; a normally ineffective locking means for the release shaft; a totalizer including a plurality of plus wheels and a plurality of minus wheels; means controlled by the totalizer when the totalizer has a positive or a negative amount thereon to render said locking means effective to lock the machine release shaft to thereby prevent release of the machine for certain types of operations; means operable upon conditioning the machine for a total-taking operation to render the locking means ineffective so that the machine may be released for a total-taking operation; means to again render the locking means effective upon completion of the total-taking operation, said last means including devices settable during the total-taking operation and effective to reenable said locking means to prevent movement of the release shaft for an entry operation of a subsequent transaction, after said totalizer is reset to zero during said total-taking operation.

2. In a machine of the class described adapted to make a plurality of operations to complete a single transaction, said operations comprising adding, subtracting, and total-taking operations, the combination of a machine release shaft; a normally ineffective locking means for the release shaft; a totalizer including a plurality of plus wheels and a plurality of minus wheels; means controlled by the totalizer when the totalizer has a positive or a negative amount therein to render said locking means effective; means operable upon conditioning the machine for a total-taking operation to render the locking means ineffective so that the machine may be released for a total-taking operation; means to again render the locking means effective upon completion of the total-taking operation, said last means including devices settable during the total-taking operation and effective to reenable said locking means to prevent movement of the release shaft for an entry operation of a subsequent transaction, after said totalizer is reset to zero during the total-taking operation; and means operable as a preliminary to the entry of said subsequent transaction to render said locking means ineffective.

3. In a machine of the class described adapted to make a plurality of operations to complete a single transaction comprising adding operations, subtracting operations, and a total-taking, or reset, operation, the combination of a machine release shaft; a normally ineffective locking means for the release shaft; a totalizer including a plurality of plus wheels and a plurality of minus wheels; means controlled by the totalizer when the totalizer has a positive or a negative amount therein to render said locking means effective; means operable upon conditioning the

machine for a total-taking operation to render the locking means ineffective so that the machine may be released for a total-taking operation; means to again render the locking means effective upon completion of the total-taking operation, said last means including devices settable during the total-taking operation and effective to reenable said locking means to prevent movement of the release shaft for an entry operation of a subsequent transaction after said totalizer is reset to zero during said total-taking operation; means operable as a preliminary to the entry of said subsequent transaction to render said locking means ineffective; and means operable during the entry of said subsequent transaction for restoring said reenabling means to its normal position.

4. In a machine of the class described, adapted to make a plurality of different types of operations to complete a single transaction comprising adding operations, subtracting operations, and a total-taking, or reset, operation, the combination of a plurality of control means for releasing the machine for the different types of operations; a machine release shaft; a normally ineffective locking means for said release shaft; a crossfooter; means controlled thereby for rendering said locking means effective during an adding or subtracting operation when the crossfooter is out of zero or normal position at the end of said adding or subtracting operation to prevent certain of said control means from releasing the machine through said release shaft for another operation of the same type; means operable upon conditioning the machine for a total-taking operation to render the locking means ineffective so that the machine may be released for a total-taking operation; means to again render the locking means effective upon completion of the total-taking operation, said last means including devices settable during a total-taking operation and effective to reenable said locking means to prevent an immediate adding or subtracting operation after said totalizer is reset to zero during said total-taking operation; and means controlled by one of said control means and operable as a preliminary to such an immediate adding or subtracting operation to render said locking means ineffective for such an operation.

5. In a machine of the class described, adapted to make a plurality of different types of operations to complete a single transaction comprising adding operations, subtracting operations, and a total-taking, or reset, operation, the combination of a plurality of control means for releasing the machine for the different types of operations; a machine release shaft; a normally ineffective locking means for said release shaft; a crossfooter; means controlled thereby for rendering said locking means effective during an entry type of operation when the crossfooter is out of zero or normal position at the end of said one type of operation to prevent certain of said control means from releasing the machine through said release shaft for another operation of the same type; means operable upon conditioning the machine for a total-taking operation to render the locking means ineffective so that the machine may be released for a total-taking operation; means to again render the locking means effective upon completion of the total-taking operation, said last means including devices settable during a total-taking operation and effective to reenable said locking means at the end of said total-taking operation to prevent an immediate

entry operation of said one type; means controlled by one of said control means and operable as a preliminary to such an immediate entry operation of the last-mentioned type to render said locking means ineffective for such an operation; and means operable during such an immediate entry operation for restoring said retaining means to its normal position.

6. In a machine of the class described, the combination of a machine release member; a normally ineffective means adapted when effective to lock said release member against operation; means for holding said locking means in its ineffective position; a crossfooter adapted to be moved into and out of engagement with its actuators; means controlled by the crossfooter and adapted to move the holding means into an ineffective position while the crossfooter is being disengaged from its actuators; resilient means for rendering the locking means effective when the holding means is moved into its ineffective position; means for retaining the holding means in such ineffective position; means for temporarily rendering the locking means ineffective while said holding means is retained in its ineffective position, said locking means being again rendered effective by said resilient means when the last means is inactive; means for releasing said retaining means; and means for restoring said holding means to normal effective position when the retaining means is released to again render the locking means ineffective.

7. In a machine of the class described having an add-and-subtract totalizer, and means to add and subtract in said totalizer and to reset said totalizer to zero, the combination of a machine release shaft; a notched disk in each denominational order of said totalizer, said disks having their notches alined when the totalizer is standing at zero; means movable into engagement with the notches in the disks when the disks are alined and engaging an unnotched section of any one of the disks when the notches are not alined; a normally ineffective locking device movable into a position to be effective to prevent operation of the machine release shaft for add or subtract operations; an element normally maintaining said locking device in ineffective position; a projection on said means positioned, by the unnotched section of any disk, into operating connection with said element; power means to thereafter move the said means to cause the projection to move the element out of normal position to thereby cause the locking device to move into effective position; means, movable when conditioning the machine for a reset operation, to move the locking device into ineffective position so that the machine can be released for reset operations; and means settable during a reset operation to maintain the element in moved position after the totalizer has been reset to zero and the notches in the disks are alined to thereby maintain the locking device in effective position upon completion of the reset operation.

8. In a machine of the class described having an add-and-subtract totalizer, and means to add and subtract in said totalizer and to reset said totalizer to zero, the combination of a machine release shaft; a notched disk in each denominational order of said totalizer, said disks having their notches alined when the totalizer is standing at zero; sensing pawls coacting with the notched disks to sense for the notches in the disks and movable into one position when all

the sensing pawls enter notches and movable into another position when one or more sensing pawls engage an unnotched section of the disks; a normally ineffective locking device movable into position to arrest the releasing movement of the release shaft; an element movable by the sensing pawls after one or more of the sensing pawls engage an unnotched section of one or more disks to cause the normally ineffective locking device to move into effective position; a total 10 taking key for releasing the machine for an operation; means controlled by the total taking keys to reset the totalizer to zero; connections between the total key and the locking device to move the locking device into normal ineffective 15 position, whereupon the machine may be released for a reset operation; and means settable during the reset operation to maintain the said element

in the position to which it was set by the sensing pawls to thereby cause the locking device to again become effective at the end of the reset operation with the notches alined.

RUDOLPH J. MOSER.
